US00D990344S

(12) **United States Design Patent** (10) **Patent No.:** **US D990,344 S**
(45) **Date of Patent:** **** Jun. 27, 2023**

(54) **LEVEL**

(71) Applicant: **Milwaukee Electric Tool Corporation**,
Brookfield, WI (US)

(72) Inventors: **Anthony S. Graykowski**, Belgium, WI
(US); **Samuel J. Howard**, Hales
Corners, WI (US)

(73) Assignee: **Milwaukee Electric Tool Corporation**,
Brookfield, WI (US)

(**) Term: **15 Years**

(21) Appl. No.: **29/800,291**

(22) Filed: **Jul. 20, 2021**

(57) **CLAIM**

We claim the ornamental design for a level, as shown and
described.

DESCRIPTION

FIG. 1 is a front perspective view of an embodiment of the
claimed design;

FIG. 2 is a front view of the claimed design of FIG. 1;
FIG. 3 is a back view of the claimed design of FIG. 1;
FIG. 4 is a bottom view of the claimed design of FIG. 1;
FIG. 5 is a top view of the claimed design of FIG. 1;
FIG. 6 is a left side view of the claimed design of FIG. 1;
FIG. 7 is a right side view of the claimed design of FIG. 1;
FIG. 8 is a front perspective view of an embodiment of the
claimed design;

FIG. 9 is a front view of the claimed design of FIG. 8;
FIG. 10 is a back view of the claimed design of FIG. 8;
FIG. 11 is a bottom view of the claimed design of FIG. 8;
FIG. 12 is a top view of the claimed design of FIG. 8;
FIG. 13 is a left side view of the claimed design of FIG. 8;
FIG. 14 is a right side view of the claimed design of FIG. 8;
FIG. 15 is a front perspective view of an embodiment of the
claimed design;

FIG. 16 is a front view of the claimed design of FIG. 15;
FIG. 17 is a back view of the claimed design of FIG. 15;
FIG. 18 is a bottom view of the claimed design of FIG. 15;
FIG. 19 is a top view of the claimed design of FIG. 15;
FIG. 20 is a left side view of the claimed design of FIG. 15;
and,

FIG. 21 is a right side view of the claimed design of FIG. 15.
The ornamental design which is claimed is shown in solid
lines in the drawings. The broken lines in the drawings are
for illustrative purposes only and form no part of the claimed
design.

1 Claim, 15 Drawing Sheets
